UNITED STATES PATENT OFFICE.

FREDERIC A. PALMER, OF NEW YORK, N. Y.

MATTRESS-FRAME OR BED-BOTTOM.

SPECIFICATION forming part of Letters Patent No. 237,586, dated February 8, 1881.

Application filed October 14, 1880. (No model.)

To all whom it may concern:

Be it known that I, FREDERIC A. PALMER, a citizen of the United States, residing in the city, county, and State of New York, have invented certain new and useful Improvements in Bed-Bottoms; and I do hereby declare that the following is a full, clear, and exact description thereof, reference being had to the accompanying drawings, and letters of reference marked thereon, in which—

Figure 1 is a plan view of my improved bed-bottom. Fig. 2 is a side view of the same. Fig. 3 is a vertical longitudinal section in the line *xx* of Fig. 1. Fig. 4 is a cross-section in the line *yy* of Fig. 1; and Fig. 5 is a perspective view of the adjusting-iron employed for stretching the woven-wire fabric, or other proper fabric, applied over and upon the bed-bottom frame.

My invention relates to movable frames of wood or metal, made to fit any bedstead, and used for sleeping and other purposes, on which frame woven-wire or other suitable fabric is stretched, designed to support the bedding, and to take the place of all slats, spiral-springs, and paliasses.

The object of my invention is to provide an improved movable frame or mattress, to be used in bedsteads (or to be supplied with legs and stand on the floor) in the place of slats, springs, or other appliances for the support of the bedding. On such frame is securely fastened, by nailing or otherwise, and stretched from end to end, attached or unattached to the sides at will, an elastic sheet or fabric, with the frame so constructed that the necessary tension can be obtained and the fabric held firmly in place without the aid of corner-irons, standards, or their equivalents, and at the same time rendering it impossible for the fabric to materially sag or slacken in the middle.

The following is a full and complete description of my invention, which consists of a wood or metal frame, so made, as shown in the drawings, that the end bars, *A* and *A'*, rest directly upon the side rails, *B B*, at right angles, projecting over and extending beyond the same, as represented in Fig. 1, on which frame the woven-wire or other fabric *W* is elevated and stretched from end to end in such manner that the fabric completely covers and

overhangs the side rails, *B*, and above the same. One end bar, as at *A'*, of my frame, with the fabric securely nailed or otherwise fastened thereto, is bolted firmly through the 55 side rails, *B*, as indicated in Figs. 1 and 2, as near the end of the same as practicable, while the other end bar, *A*, of the frame, with the fabric *W* securely fastened to it, is held down to the side rails, *B B*, by a bolt, *c*, said 60 bolt passing through a slot, *G*, in an adjusting-iron, *F*, which is seated in a rabbet, *g*, cut in the side rails, as shown, and therein firmly held by a bolt, *c'*, to the corresponding ends of the side rails, *B*, as represented in Fig. 3. 65

On the under side of the bar *A*, near each end thereof, is a groove, *g'*, cut at right angles with said bar, into which groove *g'* an elevated or raised part, *f*, of the adjusting-iron *F* fits firmly, thereby rendering the frame 70 stiff, firm, and immovable; otherwise the bolt *c*, passing through the adjusting-iron *F* and end bar, *A*, would act as a pivot on which the end bar would "work," and so cause the frame to be weak and unsteady. This iron *F* serves 75 three purposes, to wit: It affords the means of securing tension to the fabric *W* by a set-screw, *R*, inserted in an upright portion, *r*, of the same, which screw forces the end bar, *A*, outward, the bolt *c* in the bar sliding during such 80 act in the slot *G* in the iron *F*. It is also an intermediate means by which the end bar, *A*, and side rails, *B*, of the frame are united; and, lastly, its elevated part *f*, which fits closely into the groove *g'* made in the end rail, 85 *A*, to receive it, keeps the frame firm and stiff, and prevents the frame from wobbling or working on the bolt *c*, which passes through the end bar, *A*.

The side rails, *B B*, of my frame are cut 90 sloping at their ends, as shown, so that the end bars, when secured to the same, incline backward, thereby drawing the fabric *W* tightly across and upon the upper side and inner edge of the end bars, and so stiffening 95 and reducing the tendency of the bars to bend under strain, and preventing them from tipping inward.

The end bars, *A A'*, of my frame are crowned or cut circular, as at *i*, being wider in the center of their length than at the ends, and also project beyond the side rails, *B*, at will. This

crowned shape prevents them from bending inward at their center when under great strain due to tension of the fabric W. The groove g' in the end bar, A, is indispensable to keep 5 said bar from working pivotally on the bolt e , which passes through the bar, and the iron F, which unites the bar to the side rails, B B.

Having described my invention, what I claim as new, and desire to secure by Letters 10 Patent, is—

1. A mattress-frame or bed-bottom which comprises in its construction, first, side rails with both ends sloping outwardly, as shown; second, end bars applied upon the sloping portions of the side rails and extending beyond 15 the side rails; third, a woven-wire or other fabric, W, applied upon the end bars and extending beyond or overhanging the side rails of the frame; and, fourth, mechanism for hold-

ing the end bars in position upon the side 20 rails, and for adjusting one of the end bars in order to stretch the woven-wire or other fabric, substantially as described.

2. A side rail, B, rabbeted at one end, as at g , to receive an adjusting-iron, F, and with 25 both ends made sloping on top to compel the end bar to incline outwardly, substantially as and for the purpose described.

3. The adjusting-iron F, having an upright portion, r , threaded to admit a set-screw, R, 30 and slotted at G to receive a sliding bolt, c , and having an upward extension, f , to enter the groove g' in the end bar, A, substantially as and for the purpose described.

FREDERIC A. PALMER.

In presence of—

Wm. H. RIBLET,
MORTIMER J. ENNIS.
